JAMES WIXTED, OF PORT CARBON, PENNSYLVANIA, ASSIGNOR TO HIMSELF AND H. K. NICHOLS, OF POTTSVILLE, PENNSYLVANIA.

Letters Patent No. 70,061, dated October 22, 1867.

IMPROVED RAILWAY FROG.

The Schedule referred to in these Letters Patent and making part of the same.

TO ALL WHOM IT MAY CONCERN:

Be it known that I, JAMES WIXTED, of Port Carbon, county of Schuylkill, State of Pennsylvania, have invented an improvement in Railroad Frogs; and I do hereby declare the following to be a full, clear, and exact description of the same.

My invention consists in securing the steel points of frogs to the base-plates of the same in the peculiar manner fully described hereafter, so that the point may be firmly held in its place without detracting from the solidity and strength of the said plates.

In order to enable others skilled in the art to make and apply my invention, I will now proceed to describe the mode of carrying the same into effect, reference being had to the accompanying drawing, which forms a part of this specification, and in which—

Figure 1 is a plan view of my improved frog.

Figure 2, a vertical section on the line 1-2, fig. 1.

Figure 3, a transverse section on the line 3-4, fig. 1, and

Figure 4, a transverse section on the line 5-6, fig. 1.

Similar letters refer to similar parts throughout the several views.

As regards general form, my improved frog is similar to those of the usual construction, and consists of the cast-iron plate A secured to the track by bolts or spikes passing through lugs a, as usual, ribs or rails b and b' projecting from the upper surface, and forming a part of this plate, and these ribs being faced with steel in the ordinary manner. There is also between the ribs b and b' the usual angular projection e, with a steel facing, f, forming a continuation of the steel point d.

It is the peculiar manner of securing this steel point to which my invention especially relates. Ordinary steel points are made of a dove-tailed form at the lower edge, and are adapted to a dove-tailed recess formed in the plate A, a recess which tends to weaken the plate at a point where the greatest strength is required. On referring to fig. 2 it will be seen that the plate A has no recess for receiving the point; the plate being simply thicker at its narrow than at its broad end, so that uniformity of strength may be attained. The steel point d is placed on the thinnest portion of the plate, its extreme point extending to the edge of the thickest portion, the rear of the widest end of the point being overlapped by the end of the steel facing f of the angular projection e, as seen in fig. 2.

It is most important in all railroad frogs that the point should be so secured as to effectually resist all lateral strains; a security dependent in ordinary frogs on the recess in the plate A, which recess cannot be made without rendering the said plate defective as regards strength. To obviate this I secure to the plate A wrought-iron or steel strips m m, one on each side of the point d, by bolts, one strip fitting accurately between each rib b and b' and the point, so that the lateral strains imparted to the latter will be resisted by these strong ribs or rails instead of being communicated to a plate, A, so weakened by a recess as to superinduce its fracture.

I claim as my invention, and desire to secure by Letters Patent—

The steel point d, confined to the plate A of a frog, and between the rails or ribs b and b' of the same, by the wrought-iron or steel strips m m, all substantially as and for the purpose herein set forth.

In testimony whereof I have signed my name to this specification in the presence of two subscribing witnesses.

Witnesses:

JOHN WHITE,

W. J. R. DELANY.

JAMES WIXTED.
